UNITED STATES PATENT OFFICE.

PIETRO ROSSI, OF EASTBOURNE, ENGLAND.

DESIGN FOR A COMBINED ORNAMENT AND TEMPERATURE INDICATOR FOR RADIATOR CAPS.

Application filed June 30, 1925. Serial No. 13,957. Term of patent 3½ years.

To all whom it may concern:

Be it known that I, PIETRO ROSSI, subject of the King of Italy, and residing at Ceylon Place, Eastbourne, Sussex, England, have invented a new, original, and ornamental Design for Combined Ornament and Temperature Indicator for Radiator Caps, of which the following is a specification, reference being made to the accompanying drawing, forming part thereof.

Fig. 1 is a front elevation of a combined

ornament and temperature indicator for radiator caps embodying my new design; and

Fig. 2, a perspective looking towards the rear of the combined ornament and temperature indicator embodying my new design.

I claim:

The ornamental design for a combined ornament and temperature indicator for radiator caps as shown.

PIETRO ROSSI.
